(57) **CLAIM**

The ornamental design for a red mixing tip shaft and transparent housing combination, as shown and described.

DESCRIPTION

FIG. 1 is a perspective view of a red mixing tip shaft and transparent housing combination, showing my new design;

FIG. 2 is a front elevation view thereof, the rear elevation view being a mirror image;

FIG. 3 is a left side elevation view thereof;

FIG. 4 is a right side elevation view thereof;

FIG. 5 is a top plan view thereof; and,

FIG. 6 is a bottom plan view thereof.

The drawings, FIGS. 1–3, 5 and 6 are lined for color. The following explanation of the color is provided for clarity. The lining in FIGS. 1–3, 5 and 6 represents red. It is understood that the entire surface of the mixing tip shaft seen in the center of the transparent housing is red.
